PHARMACEUTICAL TABLET OR SIMILAR ARTICLE

William S. Tripp, Allegan, Mich., assignor to
L. Perriga Company, Allegan, Mich.

Filed May 1, 1970, Ser. No. 22,762

Term of patent 14 years

Int. Cl. D28—01; D1—02

U.S. Cl. D16—3

FIG. 2

FIG. 3

FIG. 1

FIG. 4

FIG. 5

FIG. 1 is a front elevation of the pharmaceutical tablet or similar article showing the novel ornamental design, the reverse side of the tablet is a mirror image of the side shown;

FIG. 2 is a top plan view thereof;

FIG. 3 is a side elevation thereof;

FIG. 4 is a side elevation thereof from the reverse of the side shown in FIG. 3; and

FIG. 5 is a bottom plan view thereof.

I claim:

The ornamental design for a pharmaceutical tablet or similar article, substantially as shown and described.
